(57) CLAIM

We claim the ornamental design for a scooped cosmetics applicator, as shown and described.

DESCRIPTION

FIG. 1 is a top perspective view of the claimed design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a right-side cross sectional elevation view thereof, taken along line 8-8 shown in FIG. 2.

The broken lines in the drawings illustrating the ferrule and handle depict portions of the scooped cosmetics applicator that form no part of the claimed design.
